(57) **CLAIM**

We claim the ornamental design for a beverage holder, as shown and described.

DESCRIPTION

FIG. 1 is a top perspective view of a beverage holder showing our new design;

FIG. 2 is a front elevation view thereof;

FIG. 3 is a top plan view thereof;

FIG. 4 is a bottom plan view thereof; and,

FIG. 5 is a side elevation view thereof.

The broken lines in the drawings showing a beverage can illustrate the portions of the design that form no part of the claim.
